UNITED STATES PATENT OFFICE.

FRANK B. COMINS, OF NEW BEDFORD, MASSACHUSETTS.

SHOE-LACE FASTENING.

SPECIFICATION forming part of Letters Patent No. 340,557, dated April 27, 1886.

Application filed March 1, 1886. Serial No. 193,641. (No model.)

To all whom it may concern:

Be it known that I, FRANK B. COMINS, of New Bedford, in the county of Bristol and State of Massachusetts, have invented certain new and useful Improvements in Shoe -Lace Fastenings, of which the following, taken in connection with the accompanying drawings, is a specification.

My invention relates to a device for fastening the ends of lacing-cords for boots and shoes; and it consists in the use of a stud or hook provided with prongs or other suitable means of securing it to the boot or shoe, and with a lip pendent from its outer collar or head at the side opposite the neck of said hook, in combination with a crescent-shaped or two-armed pawl or dog pivoted between the inner and outer collars or heads of said stud or hook, and arranged to grip the lacing-cord between its point and the inner surface of said lip, as will be more fully described.

It further consists in a hook or stud having suitable prongs or other means of securing the same to the boot or shoe, and provided with a lip pendent from the side of its outer collar or head opposite to its neck, in combination with a crescent-shaped pawl or dog pivoted between the outer and inner collars or heads of said stud, and a stop to limit the backward movement of said pawl or dog.

Figure 1 of the drawings represents a portion of a lace boot with my invention applied thereto. Fig. 2 is a front elevation of my improved lacing-cord fastening device drawn to an enlarged scale. Fig. 3 is a side elevation of the same. Fig. 4 is an inverted plan of the outer head and the crescent-shaped pawl, the neck being cut in section on line *xx* on Fig. 3. Fig. 5 is a sectional plan of same, and showing the lacing-cord fastened by the pawl, the cutting-plane being on line *yy* on Fig. 2; and Fig. 6 is a plan of the sheet-metal blank from which the hook is formed.

In the drawings, A A represent portions of a lace-boot front, with lacing-studs *a a*, of well-known construction, applied thereto in positions adapted to the lacing of the boot with the single lacing-cord *b*; and B is my cord-fastening hook secured to the boot-front near its top, all as shown in Fig. 1.

My improved cord-fastening hook is formed

from the blank shown in Fig. 6 by bending the prongs *c c c* downward, and the lip *d* and stop-lip *e* upward, and then bending the neck *f* until the outer head, *g*, is directly over and parallel with the inner head or base-collar, *h*, as shown in Figs. 2 and 3. The head *g* and base-collar *h* each has formed therein a hole, *i*, to receive the pivot-pin *j*, which is riveted therein, and has mounted thereon between said outer head and base-collar the crescent-shaped or two-armed pawl or dog *k*, one end of which acts as a toggle-like brace, to grip the lacing-cord between it and the inner face of the pendent lip *d*, and prevent the drawing out of the cord by virtue of the fact that the greater the strain upon the cord the harder the pawl will grip the same.

The blank from which the hook B is formed may be cut from sheet metal of a thickness equal to the desired thickness of the outer head at its center, and said blank may be subjected to pressure in suitably-shaped dies, to reduce the thickness of the inner head or base, the fastening-prongs, the pendent lip, and the edges of the outer head and give to the outer side of said outer head a convex surface, as shown; or the blank may be cut from metal of the same thickness that the base-collar is to have when finished, and the outer head may have a flat outer surface, as may be desired, without affecting the principles of my invention.

The operation of my invention is as follows: The normal position of the crescent-shaped pawl or dog *k* when the boot or shoe is upon the foot is with its upper end in contact, or nearly so, with the inner face of the pendent lip *d*, as shown in Fig. 4. If, now, the boot or shoe has been laced and it is desired to secure the end of the lacing-cord, it is drawn from the upper lacing-stud, *a*, obliquely across the front of the boot and in near proximity thereto, till said cord bears against the lower arm of the crescent-shaped pawl or dog *k*, when the cord is drawn upward and outward, which causes said pawl to be moved slightly about its pivot, so as to move its upper end away from the pendent lip *d*, and permit the cord to be drawn into the space between the lip *d* and the end of the upper arm of said pawl, where it is firmly held against any possible

attempt to withdraw it, occasioned by the strain upon the lacing-cord due to the ordinary use of the boot or shoe, as any increase of the strain upon the lacing-cord tends to cause the upper arm of the pawl to grip the cord with greater force, as will be seen at a glance upon inspection of Fig. 5 of the drawings.

What I claim as new, and desire to secure 10 by Letters Patent of the United States, is—

1. A lacing-cord-fastening device having the following elements, viz: a hook or stud having a base-collar, a neck, an outer head provided with a pendent lip and prongs or other suitable means of securing it to the boot or shoe, and a two-armed pawl or dog pivoted 15 between the base-collar and outer head of said hook, and arranged to grip the lacing-cord

between its upper end and said pendent lip, substantially as described.

2. In a shoe-lace-fastening device, the combination of a hook having the base-collar *h*, the neck *f*, the outer head, *g*, the pendent lip *d*, and the stop-lug *e*, with the two-armed pawl or dog *k*, all constructed, arranged, and 25 adapted to operate substantially as and for the purposes described.

In testimony whereof I have signed my name to this specification, in the presence of two subscribing witnesses, on this 27th day of 30 February, A. D. 1886.

FRANK B. COMINS.
